UNITED STATES PATENT OFFICE.

WILLIAM VORDERWINKLER, OF ROSELLE, NEW JERSEY.

WINDING AND REELING DEVICE.

Application filed May 11, 1922. Serial No. 560,025.

To all whom it may concern:

Be it known that I, WILLIAM VORDERWINKLER, a citizen of the United States, and resident of Roselle, in the county of Union and State of New Jersey, have invented certain new and useful Improvements in Winding and Reeling Devices, of which the following is a specification.

The principal object of this invention is to provide a new and improved device for winding or reeling yarn, thread, etc., upon cone bobbins such as are commonly used for knitting machines, which device will be simple in construction, composed of few parts and which therefore can be manufactured and sold at a low price and will not necessitate a high maintenance expense.

Another object is to provide a novel means for reciprocating the yarn or thread guiding means. A further object is to provide a means for automatically stopping the machine when the yarn supply is exhausted. Another object is to provide means for automatically stopping the machine when the bobbin has had a predetermined quantity of yarn wound thereon. A further object is to provide a convenient means for waxing the thread before it is wound upon the bobbin and

Another object is to so construct the machine that the bobbin being wound will rest upon a stationary shaft and be rotated thereon by the frictional contact of a rotating driving member with its periphery.

For the accomplishment of these and such further objects as will hereinafter be apparent to those skilled in the art to which this appertains, the invention consists in the construction, combination and arrangement of parts herein specifically described and illustrated in the accompanying drawings, wherein is shown a preferred embodiment of the invention, but it is to be understood that changes, variations and modifications may be resorted to which fall within the scope of the claims hereunto appended.

In the drawings forming a portion of this specification:—

Fig. 1 is a side elevation of a preferred embodiment of my invention.

Fig. 2 is a front view of the machine shown in Fig. 1.

Fig. 3 is a top plan view.

Fig. 4 is a detail of the bobbin driving member and the frame upon which it is mounted.

Fig. 5 is a section on the line 5—5 of Fig. 1.

Fig. 6 is a detail showing a front view of a modified form of the driving means for the reciprocating thread guide. 60

Fig. 7 is a side view of the parts shown in Fig. 6.

Fig. 8 is a section on the line 8—8 of Fig. 6.

Fig. 9 is a further modification of a cam structure for reciprocating the thread guide. 65

Fig. 10 is a section on the line 10—10 of Fig. 9.

As shown in the drawings, a frame work comprised of the uprights 10, and 11, lower braces 12, top pieces 13 and front bar 14 is provided. Mounted in journals 15 carried by the lower braces 12 is a main driving shaft 16 upon which is pivotally mounted a swinging frame 17 provided at its upper end 70 with a pair of spaced journals 18 in which is rotatably received a short shaft 19. Fixedly secured to the shaft 19 is a driving cone 20, a sheave pulley 21 being secured to the shaft 19 adjacent the upper bearing 18. 80

A laterally projecting lug 22 integral with the frame is drilled to receive securely the headed stub shafts 23 upon which are rotably mounted the idler sheaves 24 over which and the sheave 21 is trained the belt 25 85 which passes over a driving sheave 26 secured upon the main shaft 16. A bracket 27 mounted on the front bar 14 is provided with an elongated slot 28 through which the shaft 19 passes and serves as a guiding and 90 limiting means for the swinging frame 17.

A coil spring 28^a secured at its ends to an upright 11 and the swinging frame 17 normally holds the frame in a rearward position, while the frame 17 is provided with a catch 28^b 95 adapted to be engaged by the hooked end 29 of a pivoted lever 30 to hold the swinging frame in a forward position with the driving cone 20 in operative engagement with the bobbin 31, and a handle 17^a is secured to the 100 frame 17 and extends forwardly to a convenient point to permit the operator to swing the frame forwardly into operative position from the front of the machine.

A bracket 32 is suitably secured to the 105 front face of the front bar 14 and is provided with the guide ways 33 upon which is slidably received the bobbin carriage 34 upon which is mounted a stationary bobbin shaft 35 which preferably is tapered 110

shown in the drawings to fit within the tapered hole 36 of the bobbin 31. One side of the carriage is provided on its lower face with a series of ratchet teeth 38 with which 5 is adapted to be engaged by a pawl tooth 39, which projects upwardly from a lever 40, pivoted at one end as at 41, to the bracket 32 and terminating at its other end in a handle 42, a coiled spring 43 being provided between the lower face of the lever 40 and a laterally extending lug 44, to hold the pawl tooth 39 normally into engagement with the ratchet teeth 38. Situated in a slot 45, at the rear end of the bracket 32, is an idler 10 sheave 46, over which is passed a rope or wire 47, one end of which is secured to the bobbin carriage, as at 48, and to the other end of which is secured a weight 49. The purpose of this weight is to force the bobbin carriage rearwardly and cause the bobbin to engage with the driving cone 20.

Mounted upon a forwardly extending bracket 50, secured to one of the uprights 10, is a small spindle 51, upon which is rotatably mounted a collar 52, the spindle preferably being provided with a shoulder to hold the collar spaced from the bracket. A piece of wax 53 is rotatably received upon the spindle 51 and rests upon the collar 52, 15 weights 54 being provided, if desired, to hold the wax downwardly upon the collar. A small hooked wire 55 is secured to the bracket 50 and serves to guide the thread or yarn 56 from any suitable supply, such 20 as indicated by the numeral 57, to the wax applying device, the yarn being passed between the upper face of the collar 52 and the under face of the wax 53. By referring to Fig. 3 it will be noted that the hook 55 25 is located to one side of the axis of the spindle 51, while upon the other side of said spindle at a point substantially diametrically opposite of the hook 55, is a second guiding hook 57, which extends downwardly to one 30 side of the inner face of the bracket 50 and is pivoted as at 58 to one end of a small counterbalancing lever 59. The lever 59 is pivoted as at 60, to the lever 30, and when the yarn 56 is passed through the hook 57, 35 in its passage from the hook 55 to the reciprocating thread guide 61, it is engaged under the hook 57 holding the counterbalancing lever 59 in the position shown in Fig. 1. Should the yarn supply become exhausted or 40 should the thread break it would be evident that the tension in the yarn being released, the lever 59 would drop upon and cause the lever 30 to swing upon its pivot thus releasing the hook 57 and permitting the spring 28^a 45 to move the swinging frame 17 rearwardly and release the driving cone 20 from engagement with the bobbin 31, it being understood that the pawl 37 being in engagement with the ratchet teeth 38 will prevent 50 the bobbin from following the driving cone.

Means are also provided for releasing the driving engagement of the driving cone and bobbin when the amount of yarn wound upon the bobbin reaches a predetermined diameter and comprises a downwardly projecting lug 62 upon the lever 30 located in alignment with the weight 49. When the carriage 34 is moved outwardly by the increasing diameter of the yarn wound upon the bobbin, the weight 49 will move upwardly, as will be obvious, until the upper face of the weight reaches the lug 62, thus swinging the lever 30 and releasing the hook 69.

The thread or yarn guiding hook 61 is formed upon the end of a small metal rod 62, which is slidably and adjustably received in one end of pivoted lever 63, which is adjustably secured to a transverse shaft 64, rotatably mounted in the journal brackets 65, 85 secured to the uprights 11. Secured adjacent on end of the shaft 64, is a crank lever 64^a to which is secured a reciprocating operating rod 66, slidably mounted in the brackets 67, the lower end of the rod 66 being provided with a roller 68 adapted to engage in a uniform motion cam groove 69 formed in the outer face of a cam plate 70. The cam plate 70 is journaled upon a short jack shaft 71, suitably secured to one of the uprights 11, and is secured to a belt pulley 72 to rotate therewith, a belt 73 being trained around the pulley 72 and a driving pulley 73 secured to the main shaft 16. The cam groove is so formed as to produce a quick return movement of the thread or yarn guiding hook 61, at the upper and lower ends of its movements, and a uniform speed of movement intermediate the ends. The driving pulleys for the various parts are so proportioned as to produce about three revolutions of the bobbin to one complete reciprocation of the thread guiding hook 61.

The operation of the device is as follows, assuming the parts are in the position shown in Fig. 1, the swinging frame 17 being held in its forward position the driving cone 20 is in engagement with the bobbin 31 the bobbin being held in frictional engagement with the cone by the weight 49. The rotation of the bobbin winds the yarn 56 thereon and the reciprocation of the guiding hook 61 guides the yarn and causes it to be distributed uniformly and evenly upon the bobbin. In order to insure the proper winding of the bobbin the quick return movements at the ends of the stroke of the guiding hook, heretofore referred to are essential, as well as the uniform speed at the intermediate points. As the size of the bobbin increases the bobbin carriage 34 will move outwardly, the pawl tooth 39 being depressed at intervals by the ratchet teeth 38 and moving downwardly against the action of the spring 43. When the

weight 49 engages the lug 62, the hook 29 will be released from the catch 28^b and the swinging frame will move inwardly under the action of the spring 28^a releasing the 5 driving engagement of the cone 20 and bobbin, it being understood that the engagement of the pawl and ratchet will prevent the bobbin from following the cone. Should the yarn supply 57 become exhausted 10 or the yarn thread 56 break the release of the tension in the yarn will permit the counter-balancing lever 59 to drop and release the hook 29. After placing an empty bobbin upon the spindle 35 the operator 15 grasps the handle 17^a and pulls the frame 17 forwardly until the hook 29 is engaged, the yarn thread is threaded through the hooks 55, 57 and 61 and between the wax 53 and collar 52, a few turns of the yarn is 20 wound around the bobbin, and the handle 42 is depressed releasing the pawl and ratchet and allowing the bobbin to move forwardly into driving relation with the cone 20.

25 In Figs. 6, 7 and 8, a modified form of cam means for reciprocating the thread guiding hook 61 is shown and comprises a reciprocating rod 66^a slidably mounted in the bracket 67^a, the lower end of the rod 30 66^a being secured to a cam plate 70^a provided in its inner face with a cam groove 69^a in which is received a roller 68^a projecting from the side of crank plate 75 secured upon a jack shaft 76 journaled in 35 the upright 11^a a driving pulley 72^a being secured to the other end of the jack shaft 76 and adapted to receive a driving belt 73^a. An additional guide rod 77 is secured to the cam plate 70^a and extends downwardly therefrom being slidably mounted in 40 the bracket 78.

A further modified form of cam means is shown in Figs. 9 and 10 which form is used with a cam plate and crank disc similar to 45 that shown in Figs. 6, 7 and 8 the cam plate being provided with upwardly and downwardly extending guiding rods similar to the rods 66^a and 77. As shown in Figs. 9 and 10 the crank disc 75^a is provided with 50 a roller 68^b which projects into a cam groove 80 defined by the inner wall of a substantially figure 8 shaped recess formed in the face of the cam plate 70^b and a pair of pivoted plates 81. One of each of these 55 pair of plates is pivotally secured as by the headed screw 82 centrally of each lobe of the 8 shaped recess and each plate is provided with a tail portion 83 which is normally held in engagement with the wall 60 of the recess to project across the cam groove 80 by a bent spring 84 one end of which engages a small pin 85 projecting outwardly from the plate 81 while the other end is bent inwardly and is suitably secured in the 65 screw 86. The operation of this cam mem-

ber is as follows; assuming that the crank disc 75^a is rotating in the direction of the arrow in Fig. 9, the roller 69^b is shown approaching the tail portion 83 of the left hand plate 81, the continued rotation of the 70 crank disc will cause the roller 69^b to move the plate 81 against the action of the spring 84 upon its pivot 82, forcing the plate 81 to rotate upon the cam plate 70^a in a clockwise direction. The tail 83 will move across the 75 cam groove and will block the central portion of the groove compelling the roller 69^b to pass upwardly and across into the other lobe of the figure eight groove, it being understood that the spring 84 being placed under tension will tend to increase the acceleration produced at this point by the shape of the cam groove. It will be understood that both the cam grooves illustrated in the modifications shown in Figs. 6 to 10 are proportioned to produce an accelerated motion of the guide hook 61 at the ends of its strokes and a uniform motion driving its intermediate travel.

While the thread guiding hook 61 is shown 90 as pivotally mounted and having an oscillating motion it will be obvious that it could be mounted for a straight reciprocating motion and as the term reciprocating would also include an oscillating motion. I prefer to use the term reciprocating as referring to the motion of the hook 61.

Having thus described my invention, what I claim as new and desire to secure by Letters Patent of the United States is:

1. A device of the character described comprising a stationary frame, a bobbin mounted on said frame, a movable frame, driving means carried by said movable frame, a pivoted lever adapted to engage 105 said movable frame and hold said driving means in engagement with said bobbin, means to guide a thread under tension to said bobbin, and counterbalancing means adapted to drop upon said lever when the tension of said thread is released whereby said lever will be disengaged from said movable frame.

2. A device of the character described comprising a stationary frame, a carriage 110 slidably mounted on said frame, a bobbin mounted on said carriage, a movable frame driving means mounted on said movable frame, a pivoted lever to hold said movable frame with said driving means towards said 115 bobbin, yielding means to hold said bobbin in frictional engagement with said driving means, said yielding means adapted to engage and release said pivoted lever when said carriage reaches a predetermined position.

3. A device of the character described comprising a stationary frame, a carriage 120 slidably mounted on said frame, a bobbin mounted on said carriage, a movable frame, 125

1
driving means mounted on said movable frame, a pivoted lever to hold said movable frame with said driving means towards said bobbin, yielding means to hold said bobbin in frictional engagement with said driving means, said yielding means adapted to engage and release said pivoted lever when said carriage reaches a predetermined position, means to move said movable frame away from said bobbin when released and means to prevent said carriage and bobbins from following said movable frame when released.

10 4. A device of the character described comprising a stationary frame, driving means mounted on said frame, a carriage slidably mounted on said frame, a bobbin mounted on said carriage, means to hold said carriage with said bobbin in yielding frictional engagement with said driving means, said last mentioned means adapted to permit said carriage and bobbin to move outwardly from said driving means to compensate for the increased diameter of the thread upon said bobbin as it is being wound.

15 5. A device of the character described comprising a stationary frame, driving means mounted on said frame, a carriage slidably mounted on said frame, a bobbin mounted on said carriage, means to hold said carriage with said bobbin in yielding frictional engagement with said driving means, said last mentioned means adapted to permit said carriage and bobbin to move outwardly from driving means to compensate for the increased diameter of the thread upon said bobbin as it is being wound, means to normally urge said driving means to an inoperative position away from said bobbin, latching means to hold said driving

prevent motion of said carriage towards said driving means when said driving means moves to inoperative position.

45 6. A device of the character described comprising a stationary frame, a bobbin mounted on said frame, a movable frame, driving means carried by said movable frame, spring means for normally holding said movable frame away from said bobbin, a pivotal lever adapted to engage said movable frame and hold said driving means in engagement with said bobbin, means to guide a thread under tension to said bobbin, and counterbalancing means connected with said thread guiding means adapted to drop upon said lever when the tension of said thread is released whereby said lever will be disengaged from said movable frame and said movable frame and driving means will be moved away from said bobbin.

50 7. A device of the character described comprising a frame, a carriage slidably mounted on said frame, a bobbin rotatably mounted on said carriage, a movable frame, driving means mounted on said movable frame, a pivoted lever adapted to engage said movable frame and hold it with the driving means adjacent said bobbin yielding means adapted to hold said bobbin in frictional engagement with said driving means, means to guide a thread under tension to said bobbin, counterbalancing means connected with said thread guiding means, adapted to drop upon said lever when the tension of said thread is released and said yielding means adapted to engage said lever when said carriage reaches a predetermined point.

55 75 80 Signed at New York in the county of New York and State of New York this 10 day of April A. D. 1922.

70 WILLIAM VORDERWINKLER.
